(57) **CLAIM**

The ornamental design for a wrist brace as shown and described.

DESCRIPTION

FIG. 1 is a front, top, and right perspective view of a wrist brace showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and left perspective view thereof;

FIG. 9 is a left side elevational view the open state of wrist brace; and,

FIG. 10 is a right side elevational view the open state of wrist brace.

The broken lines shown in the drawings represent portions of the wrist brace that form no part of the claimed design.
